(57) CLAIM

The ornamental design for a zipper foldable bag (basketball shape), as shown and described.

DESCRIPTION

FIG. 1 is a front elevational view of a zipper foldable bag (basketball shape) showing my new design;

FIG. 2 is a rear elevational view thereof;

FIG. 3 is a left side view thereof;

FIG. 4 is a right side view thereof; and,

FIG. 5 is a perspective view in the state of use thereof.

1 Claim, 1 Drawing SheetFIG. 1

FIG. 2

FIG. 5
